UNITED STATES PATENT OFFICE.

HENRY F. COLVIN, OF PHILADELPHIA, PENNSYLVANIA.

STEAM-ENGINE.

SPECIFICATION forming part of Letters Patent No. 679,950, dated August 6, 1901.

Application filed December 31, 1900. Serial No. 41,587. (No model.)

To all whom it may concern:

Be it known that I, HENRY F. COLVIN, a citizen of the United States, residing at Philadelphia, in the county of Philadelphia and 5 State of Pennsylvania, have invented certain new and useful Improvements in Steam-Engines, of which the following is a specification.

The object of my invention is to construct 10 a multiple-cylinder engine employing piston-valves and wherein the valves do not have packing-rings which pass the port edges and the steam-chests do not have to be bushed or the ports bridged or gridironed to prevent the 15 packing-rings dropping into them or catching upon their edges. I also connect the steam-chests of my engine for free exhaust-passage with telescoping sleeves so arranged as to permit the free inspection of the packing-rings employed by simply unbolting the 20 steam-chest covers. The valves are connected through and within the sleeves, and only one stuffing-box is necessary for the valve-stem. There are also by-pass valves provided, which by their use enable the flow of 25 live steam into all cylinders, and by the simple movement of connected arms and their further continuous movement the by-pass valves, which are of sufficient capacity to 30 permit free fluid flowing from end to end of the cylinders to prevent creating a vacuum when the engine is running without steam, thereby obviating the necessity of employing relief-valves. The low-pressure cylinders 35 are also provided with double ports at the steam-chest end, one being for inlet and one for outlet, and the steam-chests are secured to the cylinders on flat seats to facilitate construction and renewal.

40 My invention is illustrated in the accompanying drawings shown as a multiple-cylinder tandem engine; but many of the features of construction are when applied to single-expansion engines equally effective for 45 them. Therefore I do not wish to be considered as confined to such features for multiple-cylinder engines only.

Figure 1 is a central vertical section as to most of the parts. Fig. 2 is a side elevation 50 with some parts broken to give exterior views of the piston-valves. Fig. 3 is a cross-sec-

tion on line x x , Fig. 2. Fig. 4 is a cross-section on line z z , Fig. 2. Fig. 5 is an elevation of the low-pressure-valve compression-ring in enlarged size. Fig. 6 is a top view of 55 Fig. 3, showing the breaking of the joint. Fig. 7 is a section of the joint-spring on line v v , Fig. 5. Fig. 8 is in general a central vertical section showing the position of the by-pass valves when the engine is working compound. Fig. 9 is like Fig. 8, except with the by-pass valves placed as when using live steam in all cylinders and with head 37 detached and sleeve 29 telescoped into sleeve 30. Fig. 10 is like Fig. 8, except with the 60 by-pass valves placed to open communication with the steam-ports of each cylinder to its exhaust-ports, as when running without steam or drifting.

Similar characters of reference indicate 70 similar parts throughout the views.

A high-pressure cylinder 1 is placed in line with a low-pressure cylinder 2, a piston 3 is placed in cylinder 1, and a piston 4 is placed in cylinder 2, and they are connected for co-action by piston-rod 5, while piston-rod 6 is connected to a cross-head. (Not shown.) The cylinders are joined by a connecting-sleeve 7, attached to head 8 of cylinder 2, which enters and telescopes through head 9 80 of cylinder 1 and surrounds piston-rod 7, as more fully set forth in my application filed December 24, 1900, Serial No. 40,992.

Mounted upon and secured to cylinder 1 is a steam-chest 10, covering ports 11 12 of the 85 cylinder, which connect with ports 13 14 of the chest 10. An exhaust-recess 15 is formed around the inner face of the steam-chest. The high-pressure-cylinder steam-chest 90 encloses a solid-faced truncated valve formed of piston-heads having outwardly-projecting flanges 16 17 joined to web parts 18 19. Flanges 16 17 cover and overlap ports 13 14, and the webs 18 19 are united by ties 20, (best seen in Fig. 4,) leaving an intervening 95 exhaust-space 21, corresponding to the throat of the well-known **D** form of slide-valve. Extending outward from web 18 is a trunk 22, having packing 23 near its outer end. A cross-bar 24 is also connected across within 100 the trunk 22 without preventing free fluid flowing within and beyond in the trunk,

which moves within sleeve 25, formed on steam-chest head 26, and extends therefrom both within and without. Web 19 has a similar trunk 27 extending therefrom, with a packing 28 near its outer end, and it moves within sleeve 29, formed on head 37, which extends farther outward than sleeve 25 and telescopes into sleeve 30 of head 50 of steam-chest 31, mounted on and secured to low-pressure cylinder 2. At the junction of the telescoping sleeves is formed a flange 32 on sleeve 30, and an annular ring 33 is placed over sleeve 29, the ring having its lower corner 34 beveled to press against ring 35, of soft metal, (preferably of copper wire,) to make a non-leakable union when ring 35 is forced to flange 32 and sleeve 29 by bolts 36. The object of this union of the sleeves is to enable the examination of packings 28, as when steam-chest head 37, to which sleeve 29 is attached, is removed from steam-chest 10 (see Fig. 9) sleeve 29 can be telescoped into sleeve 30, and packing 28 will be exposed and sufficient working space be obtained for its adjustment or renewal. The packing 23 is also readily exposed for like purposes by removing steam-chest head 26 and its attached sleeve 25. Steam-chest heads 26 37 have free fits within the steam-chest 10 to enable the piston-heads 16 17 to freely enter and center within circular valve-seat 38, for which purpose they are made for a close but free-moving fit, and packings 23 28 prevent the live steam from entering the exhaust-passage. Above valve-seat 38 a chamber 39 is formed across the steam-chest, and its inner end is open to and receives live steam from pipe 40, coming from saddle 41 of cylinder 2, connected to the boiler and controlled by the engine's throttle-valve. Within chamber 39 is placed by-pass valve 42, having a seat 44 at its bottom and pierced by openings 45 to permit free circulation by and around the valve. The by-pass valve has seats 46 47 at its ends, and a port 48 affords live-steam communication from the chamber 39 to the interior of steam-chest 10 through exhaust-space 21, the interior of trunk 27, and sleeves 29 30 to steam-chest 31 of cylinder 2, and passages 49 50 open therefrom directly into the interior of steam-chest 10 and the space surrounding trunks 22 27 and sleeves 25 29. At the outer end of valve 42 it has a vertical tongue 51, inserted in a groove 52 of cone 53, connected to shaft 54 and operated by arm 55, which forms a yielding connection. (See Fig. 4.) Steam-chest 31, mounted on and secured to cylinder 2, has a head 56, connected to sleeve 30, and a head 57 at its inner end with a stuffing-box 58, through which valve-stem 59 passes. Cylinder 2 has steam-ports 60 61 and an exhaust-port 62, connected to exhaust-port 63 of the steam-chest, while ports 64 65 of the chest connect with 60 of the cylinder and ports 66 67 of the chest connect with 61 of the cylinder, ports 64 66 being for exhaust and 65 67 for steam admission. A circular valve-

seat 68 is formed within steam-chest 31, and therein is placed a piston-valve comprising a central sleeve 69, fitting over valve-stem 59, heads 70 71, extending from sleeve 69, and therefrom and extending outwardly are flanges 72 73, and beyond their outer edges are followers 74 75, secured between a collar 76 and nut 77 and lock-nut 78 on stem 59, but without bearing against the ends of sleeve 69 or flanges 72 73. Heads 70 71 are beveled at their inner edges, and the followers 74 75 are beveled at their outer edges, and within the inner edges of the heads 70 71 and followers 74 75 are seats 81, wherein are placed expansion-rings 82 83, which are thicker at one side than at their opposite side, or their inner diameter is eccentric to their outer diameter, as see Fig. 5, and at the thin part, placed when in operative position at the top 84, the rings are cut across V-shaped, and underneath and resting on flanges 72 73 are springs 85 86, curved at their ends, while the tops of the springs bear under rings 82 83, making a tight joint 90 at the cut. Springs 85 86 have lips 89 90, turned up at their sides for a part of their length, and recesses 91 92 are formed in the sides of rings 82 83 to receive the lips, thus holding the springs in place and breaking the joint. The rings 82 83 fit in valve-seats 68 and are there securely held or follower-bound by the forcing of followers 74 75 to their edges by collar 76 and nut 77, locked by nut 78, and whenever rings 82 83 become worn enough to leak or permit fluid flowing by them it is simply a matter to remove head 57 and loosen nuts 78 77 to have the rings 82 83 expand to close contact with valve-seat 68, when they are again follower-bound to their working diameter, which is a free but unbreakable fit in valve-seat 68. Above and across valve-seat 68 of steam-chest 31 is a chamber 93, connected by passages 94 95 with the interior of the steam-chest, and within the chamber is a by-pass valve 96, having a seat 98 at the bottom of the chamber and pierced with openings 99. A port 100 leads from the chamber 93 to exhaust-ports 63 62 of the steam-chest and cylinder 2. A cone 101 abuts the outer end of by-pass valve 96, and a vertical recess 102 of the cone receives a tongue 103 of the by-pass valve 96, forming a yielding connection. (See Fig. 3.) A shaft 104 is formed on cone 101, and thereon is an arm 105, secured to a rod 106, which runs forward and attaches to arm 55 of the by-pass valve for cylinder 1 and back for the attachment, by which the valves are worked. With by-pass valves 42 96 in the positions as seen in Fig. 8 ports 48 100 are covered and the engine is working compound or with live steam in cylinder 1 and exhaust-steam from cylinder 1 in cylinder 2, at which time arms 55 and 105 are in the position shown in Fig. 2 and in dotted lines in Fig. 8. At such time live steam will enter chamber 39 through pipe 40, pass through passages 49 50, and enter steam-chest 10, surrounding

trunks 22 27 and the webs 18 19 and flanges 16 17 of the valve construction. When port 11 or 12 is uncovered, steam will pass to cylinder 1, and when the reverse movement of the valve takes place the port 11 or 12 will be put in communication with exhaust-space 21, thence enter trunk 27, sleeves 29 30, and steam-chest 31. Passages 94 95 and chamber 93, with the openings 99 through by-pass valve 96, will permit steam to flow to each end of the valve, where it will be admitted to ports 65 60 or to 67 61 to cylinder 2. The reverse movement of the valve will put ports 60 64 or 61 66 in communication with exhaust-ports 62 63 and the atmosphere. When it is necessary to use live steam in all the cylinders, arms 55 105 will be moved back to vertical positions, lines $z z x x$, as seen in Fig. 2, and in dotted lines in Fig. 9. This will uncover port 48 of steam-chest 10, allowing live steam to pass through and mingling with the exhaust from cylinder 1 go to chest 31 of cylinder 2, as well as to cylinder 1, through passages 49 50, but will not open port 100 of cylinder 2. When the engine is running with the steam shut off or drifting, arms 55 105 will be moved to positions A in Fig. 2 and as seen in dotted lines in Fig. 10, which will still leave port 48 uncovered by the by-pass valve 42 of steam-chest 10 and move by-pass valve 96 to open port 100 of steam-chest 31, and thus establish free communication of each end of cylinders 1 2 with their exhaust-ports and the atmosphere and prevent creating a partial vacuum within the cylinders, as is the case with ordinary piston-valves when the engine is drifting or running without steam.

I claim—

1. In an engine, multiple cylinders, pistons in the cylinders, a piston-rod to connect the pistons, a seat on each cylinder, a steam-chest secured on each seat, a circular valve-seat in each steam-chest, telescoping sleeves connecting the steam-chests, piston-valves within the steam-chests, connected through the telescoping necks for coacting, and means to move the valves.
2. In an engine, multiple cylinders, pistons within the cylinders, a common piston-rod for the cylinders, steam-chests secured to the cylinders, circular valve-seats for the steam-chests, piston-valves in the seats a common stem for the valves, and means to connect

the steam-chests by telescopic construction around the valve-stem.

55

3. In an engine, multiple cylinders, high and low pressure, pistons and rods within the cylinders, a steam-chest mounted on the high-pressure cylinder, a circular valve-seat within the steam-chest, a truncated piston-valve 60 having solid and connected piston-heads, trunks reaching outward from the heads, sleeves wherein the trunks move and which are secured to the steam-chest heads, and packing between the trunks and sleeves. 65

4. In a compound engine, multiple cylinders, pistons and rods in the cylinders, steam-chests for the cylinders, piston-valves in the steam-chests, a chamber above each steam-chest, a port from the chamber to the exhaust-passage of each chest, passage-ways from the chambers to the steam-chest's interior, by-pass valves in the chambers, and means to operate the by-pass valves for the admission of live steam to the high-pressure cylinders 75 only, as when running compound, or multiple expansion. 70

5. In a compound engine, multiple cylinders, pistons and rods in the cylinders, steam-chests for the cylinders, piston-valves in the steam-chests, a chamber above each steam-chest, a port from the chamber to the exhaust-passage of each chest, passage-ways from the chambers to the steam-chest's interior, by-pass valves in the chambers, and 80 means to operate the by-pass valves in manner to open the port to the steam-chest exhaust in the high-pressure steam-chest only, and thereby admit high-pressure steam to all the cylinders. 85

6. In a compound engine, multiple cylinders, pistons and rods in the cylinders, steam-chests for the cylinders, piston-valves in the steam-chests, a chamber above each steam-chest, a port from the chamber to the exhaust-passage of each chest, passage-ways from the chambers to the steam-chest's interior, by-pass valves in the chambers, and means to operate them and open the ports from the chambers to their steam-chests. 90 95 100

In testimony whereof I affix my signature in presence of two witnesses.

HENRY F. COLVIN.
